By their Attorneys,

UNITED STATES PATENT OFFICE.

SAMUEL F. FIELD AND JUDSON PALMER, OF FINDLAY, OHIO.

WRIST-PIN.

SPECIFICATION forming part of Letters Patent No. 618,655, dated January 31, 1899.

Application filed July 20, 1898. Serial No. 686,465. (No model.)

To all whom it may concern:

Be it known that we, SAMUEL F. FIELD and JUDSON PALMER, citizens of the United States, residing at Findlay, in the county of Hancock 5 and State of Ohio, have invented a new and useful Wrist-Pin, of which the following is a specification.

Our invention relates to wrist-pins, and has for its object to provide a simple, efficient, 10 and durable wrist-pin and stub-bearing adapted for use in connection with engine-crank pins, eccentric-rod pins, and cross-head and link pins in all kinds of machinery, the journal box or brass being adjustable with relation 15 to the stub-head or other oscillatory member to take up lost motion due to wear of the box or brass or of the wrist-pin.

Further objects and advantages of this invention will appear in the following description, and the novel features thereof will be particularly pointed out in the appended claims.

In the drawings, Figure 1 is a perspective view of a wrist-pin and connection constructed in accordance with our invention. Fig. 2 is a sectional view taken longitudinally of the stub-head. Fig. 3 is a section taken parallel with and in the plane of the axis of the wrist-pin. Fig. 4 is a detail view in perspective of 25 the sleeve forming the journal box or brass. Fig. 5 is a similar view of the collar. Fig. 6 is a detail sectional view of a portion of the sleeve to show the parallel bored outer end thereof.

Similar numerals of reference indicate corresponding parts in all the figures of the drawings.

In order that the construction, operation, and advantages of our invention may be fully 40 understood, we have shown the same in connection with the wrist-pin 1 of a crank-disk 2, 3 representing a portion of a connecting-rod or other analogous part of machinery, having a stub-head 4, which is mounted rev- 45 olubly upon the wrist-pin. The stub-head is split longitudinally to communicate with the parallel bore 5 therein, said bore forming a seat for a sleeve 6, which constitutes a journal box or brass. This sleeve is exteriorly 50 cylindrical to snugly fit in the seat of the stub-head, whereupon the tightening of the bolt 7, by which the members of the bifurcation

are connected, will lock the sleeve at the desired axial adjustment. This enables us to vary the position of the sleeve with relation 55 to the stub-head, for a purpose hereinafter explained. Also, in order to prevent movement of the sleeve independently of the seat in the stub-head, an interlocking sliding connection is formed therebetween, as by grooving 60 the sleeve exteriorly at 8 to receive a feather 9 in the seat.

The wrist-pin consists of a bearing portion 2^a, which is tapered, and the bore of the sleeve is correspondingly tapered to fit thereon, 65 whereby lost motion between the bore of the sleeve and the wrist-pin may be taken up by the axial adjustment of the sleeve. The outer portion of the wrist-pin is reduced and threaded to receive the main and jam nuts 10 and 70 11 and the collar 12, the latter having an interlocking connection with said wrist-pin to prevent independent movement of the former, such interlocking connection in the construction illustrated consisting of a feather or pin 75 13 on the collar fitting in a groove 14 in the pin. The sleeve or brass is provided with an oil-hole 15, which registers with a corresponding hole 16 in the side of the stub-head.

From the above description it will be seen 80 that while the tapered bore of the sleeve fits the tapered surface of the wrist-pin to provide for taking up wear the parallel or cylindrical exterior surface of the sleeve adapts it to be adjusted axially through the seat of the 85 stub-head to take up lost motion without affecting the alinement of the connecting-link, pitman, or other member carrying the stub-head or of which the stub-head forms a part. Thus to adjust the bearing embodying our 90 invention it is necessary simply to loosen the bolt by which the members of the stub-head are connected to release the sleeve and then tighten the nuts to secure a snug fitting of the sleeve upon the wrist-pin, whereupon the 95 tightening of said bolt will again restore the parts to their operative condition without varying the position of the pitman with relation to the plane of the crank-disk.

A further feature of construction in connection with the sleeve consists in a cylindrical portion 17 at the outer end of the bore thereof or that portion which projects beyond the extremity of the tapered portion of

the wrist-pin when the parts are first constructed. The object of this cylindrical portion of the bore is to avoid shouldering the interior of the sleeve by reason of the wearing thereof, and thus subsequently interfering with the accurate adjustment of the sleeve with relation to the wrist-pin.

The advantages of the device embodying our invention will be apparent to those skilled in the art, and it will be understood that various changes in the form, proportion, and the minor details of construction may be resorted to without departing from the spirit or sacrificing any of the advantages of this invention.

Having described our invention, what we claim is—

1. The combination with a wrist-pin having a tapered body portion, of a stub-head having an axially-transverse seat, a sleeve fitted in said seat for axial adjustment and having a tapered bore to receive said body portion of the wrist-pin, means for locking the sleeve in its adjusted positions in the seat of the stub-head, and locking devices for securing the sleeve at the desired adjustment with relation to the wrist-pin, substantially as specified.

2. The combination with a wrist-pin having a tapered body portion, of a stub-head having a seat, a sleeve fitted in said seat for axial adjustment, and having a bore tapered to fit the body portion of the wrist-pin, the outer reduced end of said tapered bore, beyond the extremity of the body portion of the wrist-pin, being cylindrical, means for securing the sleeve at the desired axial adjustment in the stub-head, and locking devices for securing

the sleeve at the desired adjustment with relation to the wrist-pin, substantially as specified.

3. The combination with a wrist-pin having a tapered body portion, of a stub-head having a transversely-contractible cylindrical seat, means for contracting said seat, an exteriorly-cylindrical sleeve fitted in said seat for axial adjustment, and having a tapered bore to fit said body portion of the wrist-pin, and means for securing the sleeve at the desired axial adjustment upon the wrist-pin, substantially as specified.

4. The combination with a wrist-pin having a tapered body portion, of a stub-head having a cylindrical seat, and also having a split in communication with said seat, a transverse bolt connecting the members of the stub-head to contract the seat, an exteriorly-cylindrical sleeve fitted in said seat for axial adjustment and having an interlocking sliding connection therewith, said sleeve also having a tapered bore to fit said body portion of the wrist-pin and means secured to the wrist-pin, beyond the outer end of the sleeve, for securing the latter at the desired axial adjustment with relation to the wrist-pin, substantially as specified.

In testimony that we claim the foregoing as our own we have hereto affixed our signatures in the presence of two witnesses.

SAMUEL F. X. FIELD.
